UNITED STATES PATENT OFFICE.

ADOLPH PETZOLD, OF PHILADELPHIA, PENNSYLVANIA, ASSIGNOR TO JOHN H. BROMLEY, JOSEPH H. BROMLEY, AND EDWARD BROMLEY, OF SAME PLACE.

DESIGN FOR A RUG.

SPECIFICATION forming part of Design No. 24,915, dated November 19, 1895.

Application filed September 14, 1895. Serial No. 562,585. Term of patent 3½ years.

To all whom it may concern:

Be it known that I, ADOLPH PETZOLD, a citizen of the United States, residing in the city of Philadelphia, State of Pennsylvania, have 5 invented and produced a new and original Design for a Rug, of which the following is a full, clear, and exact description, reference being had to the accompanying drawing, forming a part of this specification.

10 My invention relates to the surface ornamentation of a rug, and the design therefor consists of a center panel A ornamented by a composite emblem composed of a shield, a pair of flags, a star within the shield, and a 15 portrait within the star, the panel being surrounded by an ornamental border B, filling up the corners of the rectangular-shaped field.

I claim—

The design for a rug, consisting of a center panel composed of the emblems arranged as 20 shown, and an ornamental border surrounding the whole, substantially as set forth.

In testimony whereof I have hereunto affixed my signature this 7th day of September, A. D. 1895.

ADOLPH PETZOLD.
